UNITED STATES PATENT OFFICE.

EZRA W. VAN DUZEN, JR., OF NEWPORT, KENTUCKY.

STOVE OR RANGE DOOR.

SPECIFICATION forming part of Letters Patent No. 354,451, dated December 14, 1886.

Application filed March 1, 1882. Serial No. 54,001. (No model.)

To all whom it may concern:

Be it known that I, EZRA W. VAN DUZEN, Jr., a citizen of the United States, and a resident of Newport, in the county of Campbell 5 and State of Kentucky, have invented certain new and useful Improvements in Doors for Stoves or Ranges, of which the following is a specification.

This invention relates to improvements in doors for stoves or ranges, and has for its objects to provide a door of novel construction, and to provide means whereby the door, in being opened to form a horizontal shelf, is cushioned in its fall. These objects I accomplish by the construction and arrangement of parts hereinafter described and claimed, and illustrated in the accompanying drawings, in which—

Figure 1 is an elevation showing my improvement applied to cook stoves or ranges, showing but a single spring on the door. Fig. 2 is a plan view of one of the oven-door plates, with a supporting-strip placed in the recess. Fig. 3 is a central cross-section of the door. 25 Figs. 4, 5, and 6 are modifications of my improved double recessed plate door. Fig. 7 represents a broken elevation of the lower part of the oven-door, showing the manner in which I employ two springs.

30 A represents a side plate of a stove or range, in which is an opening.

B represents the oven-door. It is formed of two sheet-metal recessed plates.

a represents the outer flanged edges of the 35 recessed plates B. I have shown four modes of uniting these two recessed sheet-metal plates. Fig. 5 represents the common or preferred form, which shows the flanges a' of one plate as being bent around, over, and lapping

40 upon the flange a of its opposite plate, with the rivets c passing through the three thicknesses of metal, to hold the two plates firmly together. The object of bending over the metal of one flange to rest upon the other 45 is, first, to furnish a smooth-finished edge for the door and to prevent the spreading apart of the two metal plates, and, second, to furnish a suitable rim around the edge to strengthen the door. In Fig. 4 I show the flanges a a' of 50 the same shape, around the edges of which is a U-shaped piece of metal, a², all united by

rivets c', passing through the four thicknesses of metal to form the rim. I consider this the equivalent of the mode of flanging and fastening the recessed plates shown in Fig. 5. Fig. 55 6 represents another modification, which consists in providing an additional stiffening and supporting plate, d, which is a flat piece of metal of the same size as the recessed plate b, and resting between the flanges a a', to which 60 it is united by rivets. Instead of the plate d for stiffening the plates of the door, a bent strip or ribbon of metal, E, having the same vertical depth and lying within the recess between the plates b b', as shown in Figs. 2 and 3, 65 may be used. This stiffens and prevents the collapsing of the recessed plates. These different methods of supporting the metal plates are not in all cases essential; but they make a much stiffer door.

70 A door constructed of the two recessed plates of sheet metal, b b', has several advantages over other marginally-flanged and hollow sheet-metal doors.

First. The air-space between the plates prevents the waste of heat by radiation through the door. The inside sheet being much the hottest, the recess allows the metal to contract and expand without warping the door.

Second. A light door is provided.

75 Third. The rim of the door has sufficient yielding capacity to cause the door to yield to any inequalities in the face of the stove-plate surrounding the oven-opening, securing a perfect fit and seating of the oven-door upon the 80 stove-plate, making tighter joints than could be secured by an unyielding or rigid rim or frame, to which sheet-metal plates are usually riveted.

H H represent hinges connecting the door 85 to the plate A.

D represents springs, one end of which is attached to the door B and the other to stove-plate A in such a manner that the recoil of the spring will hold the door in a closed position. These springs also serve to cushion the drop of the door and prevent the hinges from being broken off when the door is opened. I have shown two springs, which are preferable in large ranges; but in an ordinary cook-stove, 90 and with small doors, one spring will be sufficient.

In order to sustain the oven-door in a horizontal position to serve as a shelf for supporting pans and other articles, I provide jointed links or supports I I, attached at one end to the stove-plate and at the other end to the oven-door; but I make no broad claim to such features, as they constitute the subject-matter of a separate application for Letters Patent filed by me July 8, 1881.

10 By making my oven-door plates recessed and united as shown, very thin sheet metal may be employed, not only lessening the cost, but increasing the efficiency of the door and stove.

A stove-door has heretofore been arranged 15 to slide in bearings on a stove and subjected to the action of a coiled spring arranged at one edge of the door, for the purpose of throwing the latter to a closed position as soon as released; but such does not constitute my invention. A glass face-protector for ranges has been pivoted at its lower corners, and counterbalanced by means of weights, cords, and pulleys; but neither does such constitute my invention.

25 It will be observed that in my invention the oven-door is hinged below the oven-opening, and the spring is attached at one end to or seated against the lower portion or edge of the hinged door, while the other end of said 30 spring is attached to the stove-plate. The effect of this arrangement and combination is such that when the door is swung open to act as a horizontal shelf for supporting pans it is cushioned in such movement, and but little 35 effort is required to bring it into a horizontal position. At the same time the door will not be raised from a horizontal position until manipulated by the attendant, and when this is done the spring comes into active operation 40 and aids in closing the door; and, further, when the door is closed, the tendency of the spring is

to retain it in such position. It will thus be seen that the arrangement and combination accomplish important results, and are the means of rendering the range very desirable to house- 45 keepers. By my invention I avoid the necessity of changing the construction of the range, and the improvements are capable of being applied to ranges already constructed without the application of any complicated or expensive means for attaching the spring.

I claim—

1. An oven-door for a stove or range formed of two sheet-metal plates, the bodies of which are recessed to form depressions, and their 55 edges forming flanges united together, with the depressions in the plates opposite each other, so as to form an intervening air space or spaces between the plates, and a supporting-ribbon between the recessed plates for 60 strengthening the door, substantially as herein set forth.

2. In a stove or range having an oven-chamber, the combination therewith of an oven drop-door, hinged below the oven-opening to 65 the stove-plate, a spring seated at one end upon the oven-door adjacent to its lower edge, and at its other end seated upon the stove-plate below the oven-opening, for cushioning the fall of the door to a horizontal position 70 for forming a shelf, and link-supports secured at one end to the stove-plate adjacent to the sides of the oven-opening, and at their other end connected with the door, substantially as and for the purpose described.

In testimony whereof I have hereunto set my hand in the presence of two subscribing witnesses.

E. W. VAN DUZEN, JR.
